AIR FEED FOR ROCK DRILLS

John C. Curtis, Garfield Heights, Ohio, assignor to The Cleveland Rock Drill Company, Cleveland, Ohio, a corporation of Ohio

Application June 5, 1933, Serial No. 674,395

1 Claim. (Cl. 121—9)

This invention relates broadly to rock drills, but more particularly to fluid actuated mechanism for rock drills of the drifter type.

One object of this invention is to provide means 5 for cushioning the feed piston at the extreme end of its stroke within the cylinder.

Another object of this invention is to provide 10 pneumatic cushioning means adapted to reduce the traveling speed of the feed piston within its cylinder, when the former has reached the vicinity of one end of the latter.

Another object of this invention is to produce 15 an improved feeding mechanism for rock drill wherein cushioning means are provided to prevent the abrupt termination of the stroke of the feed piston within its cylinder.

Other objects and advantages more or less ancillary to the foregoing reside in the specific 20 construction and aggroupment of the elements peculiar to this structure, as will become apparent from a more complete examination of this specification.

In the drawings which illustrate a preferred 25 embodiment of the invention:

Fig. 1 is a longitudinal view partly in section illustrating the machine assembly.

Fig. 2 is an enlarged cross sectional view taken in a plane indicated by line 2—2 in Fig. 5.

Fig. 3 is an enlarged sectional view of the right 30 end of the feeding mechanism illustrated in Fig. 1.

Fig. 4 is an enlarged sectional view of a portion 35 of the feeding mechanism, illustrating the feed piston approaching the end of its stroke.

Fig. 5 is a view similar to Fig. 4, illustrating the feed piston closer to the end of its stroke.

Referring to the drawings in which like characters 40 designate corresponding parts throughout the several views, 10 represents a rock drill of the drifter type having a piston reciprocably mounted therein and capable to deliver its blows to a cutting tool 11. The lower portion of the cylinder of the rock drill 10, is formed with a duality of ribs 12 disposed in parallelism and capable 45 of slidable engagement into corresponding ways 13, formed in the air feed tube or mounting 14. This feed tube is preferably formed of rectangular cross section, and has disposed within the extreme left end thereof a back head 15, secured 50 therein by means of bolts 16. To prevent the escape of the pressure fluid between the internal wall of the feed tube and the back head, there is a packing 17, secured to the back head by means of bolts 18. Rotatably mounted within the 55 back head 15, there is a throttle valve 19 formed

with a shank protruding to the exterior of the feed tube and adapted to receive a handle 20. The throttle valve 19 is formed with a centrally disposed bore or chamber 21 into which pressure fluid may be admitted through an inlet connection or conduit 22, which is secured to the side of the feed tube, by a nut 23. Leading from the chamber 21 to the peripheral wall of the throttle valve 19, there are two inlet ports 24 and 25 located in juxtaposed vertical plans. Disposed 10 within each of these plans, the throttle valve is also provided with two circular recesses 26 and 27, the purpose of which will be explained later. Affording constant communication of the recess 26 with the atmosphere, there is a passage 28, 15 while the recess 27 is also in constant communication with the atmosphere through another passage 29.

Disposed within the feed tube 14 at a convenient distance from the back head 15, there is a front head or bushing 30, being secured therein by transversely disposed bolts 31. This front head is provided with a centrally disposed bore 32, through which a tubular feed piston rod 33 is free to slide. To prevent the escape or leakage 20 of the pressure fluid between the internal wall of the tube 14 and the front head 30, or between the piston rod 33 and the internal wall of the bore 32, there is a packing 34 secured to the one side of the front head 30 by a retainer 35. This packing is formed with a duality of lips capable 25 of fluid tight engagement with the internal walls of the feed tube and with the external wall of the piston rod 33. The other side of the front head 30, is formed with a counterbore having disposed 30 therein a wiper 36, preferably made of fibrous material such as felt, and secured therein by a 35 spring clip retainer 37.

One end of the rod 33 is formed with an externally threaded portion adapted to receive, in 40 screw tight engagement therewith, a retainer 38 and nut 39. Clamped between these two last parts, there is a piston 40 having secured on each side thereof a packing 41 and 42. Reciprocably mounted within the interior of the tubular rod 33, there is a stem 43, formed with an enlarged and restricted portion constituting at their intersection a shoulder 44. The nut 39 is formed 45 with an aperture 45 through which the restricted portion of the stem 43 is free to pass into the feed tube 14. This outward movement of the stem is limited by the engagement of its shoulder 44 with the nut 39. The stem 43 is normally maintained in its outward position by the effort 50 of a compression spring 46 disposed within the 55

rod 33 and secured therein by any suitable means, as for instance by means of a cross pin 47. Opening into the free end of the restricted portion of the stem 43, there is a restricted port 48 leading 5 into the side of the stem. Secured to the other end of the rod 33 by means of a screw 49, there is a lug 50 formed integral with the front end of the rock drill 10, by which the movement of the rod is transmitted to the drill.

10 Disposed within the back head 15, and leading from the throttle valve into the left end of the feed tube 14, there is a passage 51 adapted to be closed by the free end of the stem 43. Affording communication between the throttle valve and 15 the right or front end of the feed tube 14, there is a passage 52 and conduit 53.

During the operation of the machine, assuming the throttle valve to be positioned as illustrated in Fig. 4, pressure fluid from the throttle valve 20 chamber 21 is admitted into the front end of the feed tube 14, through the throttle valve passage 25, port 52 and conduit 53. Pressure fluid admitted into that portion of the feed tube will act on the front head packing 34 and piston packing 25 41, thus preventing the escape of the pressure fluid from the front portion of the feed tube. The piston 40 being subjected to the action of the pressure fluid will be driven rearwardly or toward the back head 15. The movement of the piston 30 40 is transmitted to the rock drill 10 by the medium of the piston rod 33 and lug 50, affording, in this instance, the rearward movement of the rock drill. To permit a free rearward movement of the piston 40, the pressure fluid previously admitted into the rear portion of the feed tube as well as the atmosphere remaining therein is 35 free to exhaust to atmosphere through the passage 51, throttle valve recess 26 and passage or vent 28. It will be seen that if the piston 40 were permitted to reach the end of its rearward stroke 40 without restriction, the piston would strike the back head 15, causing thereby an abrupt termination of the travel of the rock drill and imparting to the mechanism undesirable and injurious vibrations. In the present construction, 45 before the piston 40 reaches the end of its rearward stroke, the free end of the stem 43 is capable of engagement with the head 15 and adapted to close the passage 41 as shown in Fig. 5. The 50 port 48 opening into the free end of the stem is capable of communication with the restricted passage 48. The relatively free exhaust of the pressure fluid through the passage 51, is now forced to take place through the restricted passage 48, thus permitting the fluid remaining into 55 the rear end of the feed tube to be compressed by the piston, and consequently affording a cushioning effect preventing the piston to strike the back head 15. During this occurrence, the speed of

travel of the piston will gradually be diminished. This reduction in the speed of travel of the piston will also be transmitted to the rock drill, thus permitting the operator to notice that the piston has reached the end of its stroke. In this instance, the operator may turn the throttle valve into neutral position or in the position illustrated in Fig. 5. In this position of the throttle valve, pressure fluid from the throttle valve chamber 21 is admitted into the rear end of the feed tube 14 through the throttle valve passage 24, passage 51 and restricted port 48. The free end of the stem 43 is still maintained in engagement with the back head 15 by the effort of the compression spring 46. Since the admission of the pressure fluid is restricted 15 through the passage 48, the piston 40 will be driven forwardly at a reduced rate of speed. When the nut 39 finally engages the shoulder 44, the stem 43 will be moved away from the back head 15, permitting thereby a free admission of 20 the pressure fluid into the rear end of the feed tube 14, through the passage 51, and the consequential unrestricted forward movement of the piston 40 and rock drill 10. During the forward movement of the piston 40, the fluid within the 25 front end of the feed tube 14 is free to exhaust to the atmosphere via the conduit 53, passage 52, throttle valve recess 27 and vent 29.

Although the foregoing description is necessarily of a detailed character, in order to completely set forth the invention, it is to be understood that the specific terminology is not intended to be restrictive or confining and it is to be further understood that various rearrangements of parts and modification of structural detail may 30 be resorted to without departing from the scope or spirit of the invention as herein claimed.

I claim:

In a drilling apparatus, the combination, with a drilling motor, of a fluid actuated feeding mechanism for said motor including a feed tube, a feeding element reciprocable within said feed tube, a member associated with said feeding element and said drilling motor for transmitting the reciprocation of the former to the latter, a throttle valve 40 housing secured within one end of said feed tube having a throttle valve rotatable therein, passages controlled by said throttle valve for admitting or exhausting pressure fluid into or out of said feed tube for actuating said feeding element, and means carried by said feeding element capable of engagement with said valve housing for automatically and regularly reducing the exhaust of the pressure fluid from said feed tube when said feeding element approaches one end thereof, reducing thereby the traveling speed of said feeding element.

JOHN C. CURTIS.
